DOEHLER DIE CASTING COMPANY, OF BROOKLYN, NEW YORK, A CORPORATION
OF NEW YORK.

METHOD OR ART OF MAKING MOLDS.

1,308,861.

Specification of Letters Patent.

Patented July 8, 1919.

Application filed January 5, 1917. Serial No. 140,708.

To all whom it may concern:

Be it known that we, CHARLES PACK and LEO FRANK NOCK, both citizens of the United States, residing at the borough of Brooklyn, in the city of New York, county of Kings, and State of New York, have jointly invented certain new and useful Improvements in Methods or Art of Making Molds, of which the following is a specification, reference being had therein to the accompanying drawings, which form a part thereof.

Our invention relates to the method or art of making molds and more particularly to making molds of plastic material for the production of machine parts.

Finished castings of low fusing white metal alloys and higher fusing alloys rich in aluminum have heretofore been made in large quantities, by what is known as the pressure die casting process. In this process steel dies are used, the casting being drawn therefrom through the separation of different parts of the mold or die. The mechanical features of the die place certain limitations upon the character, design or contour of parts which can be produced; and the rapid deterioration of the mold has precluded the advantageous commercial use of brass and bronze in the production of finished castings. To permit the production of brass or bronze machine parts upon a commercial basis, recent developments have been made in the casting art, which contemplate the use of molds made of plastic material, which molds after the metal has been poured thereinto, are broken away from the completed casting so that those limitations due to the necessity for providing for the drawing of the casting from the mold, are eliminated.

It is essential, however, to employ different methods for producing molds of different types, some castings being susceptible of production by means of sectional or split molds while others must be made by means of integral molds. The same methods, however, are not adapted for the production of different split molds. It is the practice in making split molds to use machine finished metal patterns, and the method employed in producing a mold therefrom must be such as to permit the removal of this pattern, or

a plurality of such patterns, without fracturing or chipping the plastic material of the mold.

With this condition in mind, our present invention relates to a method or art of making molds from a pattern or patterns requiring that a portion of the mold cavity be formed in one section of the mold, and a portion thereof in another section of the mold in a manner to secure a perfect match of the mold cavities in the two sections. A mold made in accordance with our invention adapts itself to the production of a plurality of castings at one pouring. The chilling of the metal is so controlled as to insure the filling of the mold and the gate is so formed as to facilitate the flow of the metal to the various mold cavities so as not to interfere with the drawing of the several patterns.

A mold made in accordance with our invention possesses a sufficient degree of porosity to afford ample venting facility, and a large number of such molds may be rapidly and economically produced and all will possess such exactitude in the dimension and arrangement of the various mold cavities as to insure uniformity in the results from casting operations in different molds.

The invention consists primarily in a method or art of making molds consisting in placing a pattern within a frame upon a slab, flowing a plastic composition into the frame, agitating said plastic composition about the pattern, allowing the composition to set, reversing the frame with the plastic mass therein, positioning a gate pattern thereon with a lead thereof in engagement with the pattern embedded in the plastic composition, placing a second frame upon said first frame, flowing plastic composition into said last named frame, allowing said composition to set, separating the frames and drawing the patterns from the plastic mass in each of said frames; and in such other novel steps and practices as are hereinafter set forth and described and more particularly pointed out in the claims hereto appended.

Referring to the drawings:—

Figure 1 is a vertical section through a portion of a mold ready for the separation of the frames and the drawing of the patterns;

Fig. 2 is a plan view of the lower section of the mold;

Fig. 3 is a bottom plan view of the upper section of the mold;

5 Fig. 4 is a perspective view of one of the patterns used; and

Fig. 5 is a plan view of the gate pattern.

Like letters refer to like parts throughout the several views.

10 In the commercial practice of our invention, it is customary to produce a mold having a plurality of cavities therein and in the accompanying drawing, we have illustrated such a mold. In the practice of our

15 method or art, we place a plurality of patterns such as *a* within a frame *c* adapted to confine a sufficient mass of the plastic composition and upon a flat slab *b*, the face of which conforms with the lower face of the

20 pattern so as to prevent the fluid or viscous composition entering beneath the pattern. Each of the patterns *a* is provided with a stem *a'* projecting to substantially the height of the frame *c* so as to facilitate the drawing

25 of the patterns. Thereafter a plastic composition preferably consisting of plaster of Paris, kieselguhr or cellite and a fluid is flowed into the frame *c* to approximately the level of the top thereof. While the said

30 plastic composition is still fluid it is agitated about each of the patterns to free any air which may be imprisoned in angles or cavities therein and after being so agitated the plastic mass *d* is allowed to set.

35 When the plastic mass has set in the manner above referred to, the mold is inverted exposing one face of the patterns and a smooth surface of the plastic material which has set against the slab.

40 When the frame *c* has been thus inverted, a pattern having a main ingate *e*, a wide run *e'* and branch gates *e''* is placed upon the plastic mass *d* with the said branch gates *e''* resting upon the patterns *a* respectively.

45 A second mold frame *f* is then superimposed upon the frame *c* and plastic composition of the character above referred to is flowed into said frame *f* upon the plastic mass *d* and about the exposed tops of the patterns *a* and the gate pattern. If desired this plastic composition while still in a fluid state may be agitated about the top of the patterns *a* to free any imprisoned air, and thereafter the plastic is allowed to set.

50 When the plastic in the mold *f* has solidified to the desired extent, the mold sections are separated, there being no tendency of the plastic mass *g* within the frame *f* to bond to

60 the plastic mass *d* in the frame *c*. After the frame has been thus separated the pattern *e* is drawn from the mass *f* and the several patterns *a* are drawn from the mass *d* by inverting the same and applying rectilinear stresses to the projections *a'*. There-

after the mold is heat dried in the usual manner.

The projections *a'* form chill openings exposed through what becomes the bottom of the mold in pouring so that by resting the 70 mold upon a surface of metal or metal coated with a thin layer of refractory material, the chilling of the casting is effected at a point remote from the ingate to each mold cavity, and any tendency in the chilling of the mold 75 about the ingate in a manner to interfere with the proper filling of the mold cavity is avoided.

The arrangement of the main ingate *e*, run *e'* and branch gates *e''* is such as to prevent 80 oxids or other dross entering the mold cavity, the main ingate being large in section relative to the run *e'* and branch gates *e''*, so that there will be a slight retardation of the flow, or skimming action, in the 85 main ingate, causing the pure metal to drop through the main ingate while the lighter dross is held up. Also by forming the gate in the manner described the sprues upon the castings will be so positioned as to be 90 readily removed without interfering with the parts of the casting having small dimensions or requiring accuracy of dimension.

The surplus metal formed by the section 95 of the mold cavity produced by the extensions *a'* may readily be removed, the drilling of the hub, when a gear is made, (and the method of making the mold is especially adapted for the production of gears) removing this surplus metal. 100

In casting, the ordinary pouring methods may be employed, the castings being drawn from the mold by the breaking down of the plastic mass about same.

A mold made in accordance with our invention may be used for casting metals having either low or high fusing points and the same patterns may be repeatedly used in making a number of molds. By using the projections *a'* which are in the nature of 105 ejector pins, the stresses in drawing the patterns may be so governed, as to insure the proper draft of the pattern in leaving the mold and minimize any tendency of the breaking down of any of the small dimension projections in the mold cavity. By 110 tapering the projections or pins slightly, the necessity for providing the pattern itself with any substantial draft is avoided, as air may be admitted through the openings 115 formed by said projections or pins into the mold cavity as the patterns leave the mold, thus overcoming the effect of suction as the patterns are withdrawn.

It is not our intention to limit the invention 125 to the particular contour of the mold or patterns shown in the accompanying drawings, this showing being merely for the purpose of illustrating the practice of our method or art. Only patterns having 130

one face thereof so formed as to permit the separation of the molds, may be used in the practice of our method or art.

In molds produced in accordance with our invention, no fins are formed upon the castings because of the very fine joint secured between the two parts of the mold as a result of the use of the fluid or viscous composition in the frame *f*.

10 To secure an absolute register of the two sections of the mold, one or more cavities *h* are formed in the mass *d* by means of patterns *h'*, when forming this section of the mold, so that when the section *g* is formed 15 corresponding tongues *i* will be formed thereon.

Having described the invention what we claim as new and desire to have protected by Letters Patent is:—

20 1. The method or art of making molds consisting in placing a pattern within a frame upon a slab, flowing plastic composition into the frame, agitating said plastic composition about the pattern, allowing the 25 composition to set, reversing the frame with the plastic mass therein, positioning a gate pattern thereon with the lead thereof in engagement with the pattern embedded in the plastic composition, placing a second frame 30 upon said first frame, flowing plastic composition into the said last named frame, allowing said composition to set, separating the frames and drawing the patterns from the plastic mass in each of said frames.

35 2. The method or art of making molds consisting in placing a plurality of independent patterns within a frame upon a slab, flowing plastic composition into the frame, agitating said plastic composition 40 about each of said patterns, allowing the composition to set, reversing the frame with the plastic mass therein, superimposing a second frame upon said first named frame, flowing a plastic composition into said last 45 named frame, allowing said composition to set, forming a gate cavity in one of the mold sections thus made by positioning independent gate patterns, so that portions thereof will each engage a portion of each of said patterns, before pouring the plastic composition 50 into the frame, separating the frames after the composition within the last named frame has set, drawing each of said first named patterns and said gate patterns from the plastic mass and forming coöperating tongues and sockets in said mold parts respectively by forming a cavity in the mass of plastic composition in said first named frame by means of patterns placed upon the 55 slab prior to the pouring of the plastic composition forming said mold part whereby the filling of the superimposed frame with plastic composition will cause registering tongues to be formed by the plastic mass in 60 the other mold section.

55 3. The method or art of making molds consisting in placing a pattern within a frame upon a slab, flowing plastic composition into the frame, agitating said plastic 60 composition about the patterns, allowing the composition to set, reversing the frame with the plastic mass therein, positioning a gate pattern thereon with the lead thereof in engagement with the pattern embedded in the 65 plastic composition, placing a second frame upon said first frame, flowing plastic composition into the said last named frame, allowing said composition to set, separating the frames, drawing the patterns from the 70 plastic mass in each of said frames, forming a chill opening leading from a mold cavity formed in the mold part made in said first named frame and opening downwardly 75 thereof whereby the initial chilling of the 80

frame upon said first frame, flowing plastic composition into the said last named frame, allowing said composition to set, separating the frames, drawing the patterns from the plastic mass in each of said frames, and 70 forming coöperating tongues and sockets in said mold parts respectively by forming a cavity in the mass of plastic in said first named frame by means of a pattern placed upon the slab prior to the pouring of the 75 plastic composition forming said mold part whereby the filling of the superimposed frame with the plastic composition will cause registering of the tongues to be formed by the plastic mass in the other mold section. 80

4. The method or art of making molds consisting in placing a plurality of independent patterns within a frame upon a slab, flowing plastic composition into the frame, agitating said plastic composition 85 about each of said patterns, allowing the composition to set, reversing the frame with the plastic mass therein, superimposing a second frame upon said first named frame, flowing a plastic composition into said last 90 named frame, allowing said composition to set, forming a gate cavity in one of the sections thus made by positioning independent gate patterns, so that portions thereof will each engage a portion of each of said patterns, before pouring the plastic composition 95 into the frame, separating the frames after the composition within the last named frame has set, drawing each of said first named patterns and said gate patterns from the plastic mass and forming coöperating tongues and sockets in said mold parts respectively by forming a cavity in the mass of plastic composition in said first named frame by means of patterns placed upon the 100 slab prior to the pouring of the plastic composition forming said mold part whereby the filling of the superimposed frame with plastic composition will cause registering tongues to be formed by the plastic mass in 105 the other mold section.

5. The method or art of making molds consisting in placing a pattern within a frame upon a slab, flowing plastic composition into the frame, agitating said plastic composition about the pattern, allowing the composition to set, reversing the frame with the plastic mass therein, positioning a gate pattern thereon with the lead thereof in engagement with the pattern embedded in the 110 plastic composition, placing a second frame upon said first frame, flowing plastic composition into the said last named frame, allowing said composition to set, separating the frames, drawing the patterns from the 115 plastic mass in each of said frames, forming a chill opening leading from a mold cavity formed in the mold part made in said first named frame and opening downwardly 120 thereof whereby the initial chilling of the 125

85 90 95 100 105 110 115 120 125 130

- metal will be at a point remote from the ingate of the mold cavity when pouring.
6. The method or art of making molds consisting in placing a pattern within a frame upon a slab, flowing plastic composition into the frame, agitating said plastic composition about the pattern, allowing the composition to set, reversing the frame with the plastic mass therein, positioning a gate pattern thereon with the lead thereof in engagement with the pattern embedded in the plastic composition, placing a second frame upon said first frame, flowing plastic composition into the said last named frame, allowing said composition to set, separating the frames, drawing the patterns from the plastic mass in each of said frames, and forming coöperating tongues and sockets in said mold parts respectively by forming a cavity in the mass of plastic in said first named frame by means of a pattern placed upon the slab prior to the pouring of the plastic composition forming said mold part whereby the filling of the superimposed frame with the plastic composition will cause registering of the tongues to be formed by the plastic mass in the other mold section, forming a chill opening leading from a mold cavity formed in the mold part made in said first named
- frame, and opening downwardly thereof whereby the initial chilling of the metal will be at a point remote from the ingate of the mold cavity when pouring.
7. The method of making molds consisting in placing a pattern within a frame upon a slab, flowing a plastic composition, comprising plaster of Paris, kieselguhr and a fluid, into the frame, agitating said plastic composition about the pattern, allowing the composition to set, positioning a gate pattern thereon with the lead thereof in engagement with the pattern embedded in the plastic composition, placing a second frame upon the first frame, flowing plastic composition into the said last named frame, allowing said composition to set, separating the frames, and drawing the patterns from the plastic mass in each of said frames.

In witness whereof we hereunto affix our signatures in the presence of two subscribing witnesses, this 28th day of December, 1916.
